Tulsa, Okla.

Application June 10, 1944, Serial No. 539,718

21 Claims. (Cl. 252—321)

1

This invention relates to new and useful improvements in methods of and apparatuses for treating oil well streams.

A particular object of the invention is to provide an improved method of and apparatus for defoaming oil well streams, whereby foaming is reduced to a minimum or is substantially prevented.

It is known that in many oil fields a large amount of foam is generated when gas is mixed with certain gravities of crude oil in the production thereof. This foaming is aggravated when such a stream is dumped or discharged into an accumulating area. Foaming is primarily due to the gas flowing with the oil in solution, but agitation of the stream adds to the difficulty; and this is particularly true where large quantities of gas flow with the stream.

Excessive foaming defeats efficient emulsion treating and frequently prevents adequate separation of the oil and water. In some instances the foaming is so bad that the oil and gas will not separate in an oil and gas separator, thus causing objectionable quantities of oil to escape with the gas from the separator. It has been found that by degassing the well stream under the proper conditions, foaming will substantially be eliminated.

An important object of the invention is to provide an improved method and apparatus whereby, the foaming well stream is heated to release gas in solution, preferably by passing the stream through a body of heated water; and also in aggravated cases passing the stream through a medium whereby, the oil globules are ruptured or broken up to more effectually release the dissolved gas.

Another object is to control the temperature of the heating liquid in accordance with the composition of the particular mixture being treated in order to release sufficient gas to eliminate foaming, or substantially so. It is known that quantities of gas in solution, depending upon the particular mixture, cannot be released without lowering the gravity of the oil; however, unless gas in solution is released, there will be foaming. Also different degrees of heat are required to release sufficient gas from different mixtures to eliminate foaming. Thus, the control of the temperature of the heating medium becomes highly important.

In instances where the gas is to be taken to a gasoline plant, or otherwise processed, it may be more profitable to release large quantities of dissolved gas from the oil, even though the

2

gravity of the oil conducted to the stock tank is lowered; however, where it is more desirable to deliver the oil with the highest gravity obtainable, or to restore gravity to the treated oil, the released gas must be again mixed with the oil. It is therefore one of the objects of the invention to reabsorb the gas in the treated oil to raise or restore the gravity of the oil.

It is also desirable to produce a treating unit of some flexibility thus permitting it to be moved from one location to another location. Also it may be desirable to carry off the free gas before discharging the influent liquids into a body of previously accumulated liquids. Therefore, another object of the invention is to provide a treating unit, whereby a relatively small gas separator may be attached to it and the influent delivered to this separator before discharging it into the defoaming chamber; said influent either being preheated or not preheated.

A construction designed to carry out the invention will be hereinafter described together with other features of the invention.

The invention will be more readily understood from a reading of the following specification and by reference to the accompanying drawing, wherein an example of the invention is shown, and wherein:

Figure 1 is a schematic view partly in elevation and partly in vertical section, showing an apparatus for carrying out the invention.

Figure 2 is a horizontal cross-sectional view taken on the line 2—2 of Figure 1.

Figure 3 is an inverted horizontal cross-sectional view taken on the line 3—3 of Figure 1.

Figure 4 is a transverse vertical sectional view of the treater unit showing a gas separator mounted thereon.

Figure 5 is a view partly in elevation and partly in section, showing another form of apparatus, and

Figure 6 is a similar view of still another form of apparatus.

In the drawings (Figs. 1 to 4), the numeral 10 designates an upright tank mounted on an annular base 11 and having a dished bottom 12, which may be provided with a suitable cleanout connection 13, whereby settled and extraneous matter may be drained and washed out. The upper end of the tank is closed by a crowned head 14 having a central opening surrounded by a flanged collar 15.

A transverse dished partition 16 spaced below the top of the tank forms the bottom of a defoaming chamber A at the upper portion of the

tank. This partition separates the chamber from a washing or treating chamber B extending to the bottom of the tank. A cleanout pipe 17 leads from the center of the partition, across the chamber B and out through the wall of the tank.

An upright cylindrical preheater or heat exchanger C is mounted on the exterior of the tank similar to the heat exchanger set forth in the patent to Jay P. Walker, No. 2,181,685. This exchanger includes a lower tube sheet 18 and an upper tube sheet 19, spaced from its ends. Upright spaced tubes 20 have their ends secured in said tube sheets and open for the passage of fluids therethrough. The exchanger has an inlet 21 in its side below the tube sheet 18 for admitting the well stream. An angular pipe 22 leads from the top of the exchanger to the wall of the tank and discharges into the chamber A, above the partition 16.

An oil discharge nipple 23 connects the upper portion of the chamber B with the exchanger below the tube sheet 19, whereby heated oil accumulates in the space around the tubes 20, and thus the cooler influent fluids passing up through the tubes are warmed or heated by heat exchange 25 with the heated oil, whereby the latter is cooled. An oil discharge pipe 24 leads from the exchanger a short distance above the tube sheet 18, whereby the treated oil may be disposed of as hereinafter set forth. Just below the tube sheet 19 a nipple 25 connects the chamber B above the nipple 23, with the exchanger whereby gas may pass back and forth and pressures may be equalized.

A nozzle or spreader 26 extends across the chamber A, just above the discharge of the inlet pipe 22. This spreader may be of any suitable design and I have shown an inverted V-shaped structure provided with perforations 27 spaced therealong, preferably on each side of the ridge thereof. The purpose of the spreader is to divide the influent into a multiplicity of upwardly flowing dispersed streams. The size of these streams may be governed by the size of the perforations and the dispersion may be controlled by the spacing of said perforations.

Spaced a short distance above the spreader 26 is a transverse filter D, which may be of any construction suitable for the purpose. The structure shown includes a foraminous transverse bottom sheet 28 which may be made of wire fabric, reticulated sheet metal or wood lattice, all of which is common in the art. This bottom sheet supports a bed or transverse body of filtering material 29, such as excelsior, hay, or fibrous material. However, the filter material must be of such character, and the body of such porosity as to permit the passage therethrough of water and oil, but to break up the oil globules or bubbles and thereby free gas therefrom.

The filter body is confined by a transverse sheet 30. The sheets 28 and 30 are suitably secured at their circumferential margins to the tank wall. The sheet 30, is located at the medial portion of the chamber A and supports an upright partition 31, offset from the center of the tank. The partition 31, coacting with the tank wall and sheet 30, defines an open-top skimming tray E. That portion of the sheet 30 underlying the tray E is perforated and may be similar to the sheet 28, while the remainder of the sheet on the opposite of the partition 31 is imperforate and forms the bottom of a baffling tray F. Staggered and downwardly inclined baffles 32 are secured to the tank wall and said partition. That portion of the chamber A above the trays forms a gas space G.

A gas flow and pressure equalizing pipe 33 extends from the top of the chamber B up through the elements 16, 26, D and E to the space G.

The purpose of the defoaming chamber A is broadly, to separate oil, gas and water. As before pointed out in many oil fields a large amount of foam is generated when gas is mixed with certain gravities of crude oil; and the foaming is aggravated when the stream is dumped or discharged into an accumulating area. It is also desirable for efficient treating to carry off the free gas. By providing a body of water in the chamber A, into which the emulsified oil is discharged and by heating such body of water to from 135° F. to 190° F. (the degrees being merely exemplary) according to the particular oil being treated, much of the gas in solution with the oil will be driven off and foaming thereby reduced. Also by reducing agitation some foaming is prevented. However, the heat treatment alone, in some compositions of oil, gas and water, is not sufficient to break up the oil globules or bubbles and release the gas, and therefore the filter D is employed. This filter may be omitted if heat treatment is found sufficient for the desired results.

The dispersion and distribution of the influent is highly advantageous both in heating and filtering as it more uniformly heats the influent and more effectively releases the gas. More or less free water may flow with the emulsified oil and it is desirable to extract such water from the chamber A so that it will not accompany the oil through the remainder of the apparatus and thereby add to both the subsequent heating and treating load. While free water and gas are separated from the influent in the chamber A and foaming is reduced to a minimum, it is necessary to further treat the oil to fully break up the emulsion, particularly the tighter emulsion.

A water discharge pipe or leg 34 extends down through the tray E and filter D to a point near the partition 16, and is connected at its top with an exterior siphon box 35 by a nipple 36 extending through the tank wall. The upper end of the box is connected with the gas space G by a nipple 37. This siphon box and its operation are fully explained in the patent of Jay P. Walker, No. 2,297,297. A discharge pipe 38, having a cut-off valve 39 therein, leads down from the bottom of the box. This siphon box arrangement is located to maintain a water level in the tray E, a suitable distance below the upper edge of the partition 31 and a body of water in the chamber A below the partition 30. The emulsified oil collects on top of the water in the tray E and is skimmed off into the baffling tray F.

When it is desired to heat the water in the chamber A, a circulating heating system is employed which includes a suitable water heater H, the particular construction of which is not involved in this invention. A water discharge pipe 40 leads from the bottom of the chamber A to the heater and includes a hand valve 41; while a return water pipe 42 including a similar valve 43, leads from the heater to the tray E. When it is not desired to use the heating system the valves 41 and 43 are closed. The valve 39 may be adjusted to control the water discharge through the pipe 38 when necessary. By placing the heater H on the ground the pipe 40 will be given sufficient length and the water flowing down this pipe will cool rapidly. Thus the heating system will set up an efficient thermo-syphonic action, and the water in the chamber A will be effectively heated. Of course, the heater

may be regulated to vary the temperature to which the water is heated.

It will be observed that the gas space G is comparatively large and gas is discharged therefrom through an escape pipe 44 mounted in the head 14. The pipe 44 carries an ordinary safety valve 45, which may be set to carry a predetermined pressure within the tank. Some condensing of gaseous mixtures will occur in the space G and this will be particularly true where warmer gaseous mixtures pass from the chamber B up through the pipe 33 and commingle with the cooler gases therein. Also cooler gases may pass from the space G down into the chamber B, through said pipe. Any condensates produced in the space G will fall into the oil and thus not be lost.

The emulsified oil skimmed off of the tray E will flow down the baffles 32 in the tray F, whereby additional gas will be scrubbed out of the oil. A conductor or down pipe 46 leads from the bottom of this tray and is made of such diameter or capacity as to readily carry off the emulsified oil which flows into the tray F, thus avoiding an accumulation of oil in said tray and giving the baffles full opportunity to function in scrubbing remaining gas from the oil. By the time the emulsified oil enters the pipe 46, it will be substantially defoamed, substantially free from water and more or less quiescent.

By defoaming the emulsified oil in the chamber A, a marked advance is made in the treating of emulsified oils. Excessive foaming frequently causes quantities of oil to flow out the gas discharge lines. Where large quantities of gas flow with the well stream considerable finely dispersed oil particles and gaseous fluids are carried by the flowing gas. Where gas is in solution with the oil, oil-gas fractions are in various states or degrees of equilibrium and thus, if the volume or velocity of the discharging gas is considerable, such fractions bearing more or less oil, as well as finely dispersed oil particles, are readily picked up and carried out with the gas. In transit many of the oil-gas globules are broken up and oil may thus flow out of the gas discharge lines with the gas. Further, agitation accompanying foaming, churns the gas and accentuates its tendency to pick up oil fractions. These undesirable results are substantially avoided by the treatment in the defoaming chamber A.

It may be desirable in handling some well streams to first release and scrub out some gas before discharging the liquids into the defoaming chamber A. In Figure 4, we have illustrated a form of structure for this purpose. A small gas separator J is provided with a reduced lower end having a flange 47 which is mounted upon and bolted to the flange of the collar 15 on top of the tank 10 of Fig. 1. The interior structure of this separator is similar to the tower 26 shown in the Jay P. Walker Patent No. 2,297,297, in that it is equipped with a diverter 48, and a gas scrubbing shell 49 provided with inlet openings 50, which function substantially as set forth in said patent.

In this form (Fig. 4) the pipe 22 is provided with an extension 22' which includes a cut-off valve 90 and is connected to the diverter 48. The pipe 22 in Fig. 4 has a cut-off valve 91 which may be closed when the gas separator J is used. In case it is not desired to use the preheater, the valves 90 and 91 are closed and the influent is supplied through a pipe 92 connected to the pipe 22' and including a cut-off valve 93. A flume 51

extends from the bottom of the separator through the collar 15 into the chamber A which chamber is substantially the same in construction as in Fig. 1. The lower end of the flume may terminate in the filter bed 29, so as to discharge the liquids thereinto. A drain pipe 52 leads from the bottom of the shell 49 down through the flume to the lower end thereof. A gas flow and equalizing pipe 53 connects the top of the separator shell with the top of the gas space G in the chamber A.

The well or emulsified stream enters through the diverter 48 and is whirled around on the inner surface of the separator, whereby the free gas is released and some gas in solution is scrubbed out. The shell 49 acts more or less as a mist extractor wherein some liquid will be extracted and pass down the drain pipe 52.

The emulsified oil accompanied by the free water will flow down the separator and through the flume 51. As the filter D is immersed in the body of heated water in the chamber A the free water will gravitate toward the bottom of said chamber. The emulsified oil will flow upwardly through the filter bed 29, whereby the oil globules or bubbles will be broken up. This oil will also be heated while flowing upwardly through the heated water, with the result that sufficient gas in solution will be released to reduce foaming to a minimum. The gas released in the separator J will flow up and out through pipe 68 if valve 69 is open or down the pipe 53 and commingle with the hotter gas in the space G, if valve 69 is closed and valve 70 is open whereby some condensation of hydrocarbons will occur. If valves 69 and 70 are both open then gas will flow from the space G to the pipe 68 and escape.

The construction and operation of chamber B, wherein the emulsified oil is again heated and washed, is substantially the same as disclosed in the Jay P. Walker Patents 2,181,688 and 2,297,297. The pipe 46 which conducts the defoamed oil down into the chamber B is disposed at one side of said chamber and has a plug 54 at its bottom for clean-out purposes. Immediately above the lower end of said pipe a lateral 55 extends from the pipe to the central portion of the lower end of the chamber where it is connected to the medial portion of a spreader 56, substantially the same in construction as the spreader 26. A return flue heater 57 is mounted above the spreader and the spreader and heater are confined in the lower portion of a housing 58 as in said patents supra.

The housing 58 is provided with inclined staggered baffles 59, also with a filter 60 and return passages 61 on each side thereof, the pipe 46 being located in one of these passages. In the other passage 61, a water discharge pipe 62 extends upwardly and is connected with a siphon box 63 by a lateral 64. A gas vent pipe 65 leads from the top of the box into the gas space above the oil level in the chamber B and the top of the box is also connected with the lower end of the water discharge pipe 38 extending from the box 35. A water discharge pipe 63' extends from the bottom of the box 63.

The gas discharge pipe 44 (Fig. 1) may be connected with a pipe 66 having a cut-off valve 67 therein for the purpose of carrying off the gas from the space G of the chamber A; while a gas discharge pipe 68 (Fig. 4) having a cut-off valve 69 therein may be connected with the gas pipe 53. The pipe 53 may also be equipped with a cut-off valve 70 adjacent the head 14. It may be desirable to carry off the gas to a gasoline plant or

otherwise use it, or it may be more advantageous to admix it with the treated oil to raise the gravity thereof, or to do both. Suitable connections and adjustments may be made to attain these results and as they are obvious, further explanation is considered unnecessary.

The degree of heat employed in the chamber A is subject to a wide variation. One of the important features of the invention is the control of the temperature of the water in the chamber A and this may be done by adjusting the valve 41 in the pipe 40, by regulating the heater H or in any other suitable manner. The valve may be thermostatically controlled which is in common use in the valve art. Foaming may be substantially eliminated from some emulsified oils by heat alone, thus omitting the filter D. The temperature of the water in the chamber A may even be higher than the temperature of the water in the chamber B; however, in such event while some emulsion may be broken in the chamber A, the actual washing therein is not sufficient to completely break down the emulsion. Simply heating the water in chamber A is not sufficient. In order to eliminate foaming, the composition of the well stream should be known and the temperature controlled accordingly.

There may be conditions where the temperature to which it is desirable to heat the water in chamber A, may be approximately 130° F.; while the temperature to which the water in chamber B was heated would be approximately 120° F. In most operations, the temperature of the water in the chamber A would be lower than the temperature to which the water in chamber B is heated. As an example, the water in chamber A may be heated to approximately 130° F. and higher; while the temperature to which the water in the chamber B is heated may be approximately 140° F. or higher.

Where it is desired to admix the treated oil discharged from the heat exchanger or preheater C through the pipe 24, with the gas discharged from the space G, by way of the pipe 44 (Fig. 1), said pipe may be connected with an absorber K by means of a pipe 71. In such an instance the pipe 66 would either be omitted or the valve 67 closed. The pipe 24 would also be connected with the absorber by a pipe 12 having a cut-off valve 73 therein. An oil discharge pipe 74 having a cut-off valve 75 therein may be connected to the pipe 24. Thus, the treated oil may be conducted to the absorber or carried off to the stock tanks, by properly adjusting the valves 73 and 75.

Where the emulsified oil is heated to an appreciable degree in the chamber A as for instance as high as 160° F. to 190° F., or where the gas to oil ratio is high and/or large quantities of gas are taken off in the space G, it would be detrimental to the gravity of the treated oil not to reabsorb this gas in such oil. Of course, if the gasoline plant was available to carry off the gas or a considerable portion thereof to such a plant, the absorber would not be required. The disposition of the gas thus becomes optional.

The absorber may be of any construction suitable for the purpose. We have illustrated the absorber as including an upright vessel or tower 76 having a bottom 77 and a head 78 and mounted on a base 79. A gas escape pipe 80 leads from the head and an oil discharge pipe 31 extends from the lower end of the tower. The pipe 81 is equipped with the usual float controlled discharge valve 82. The tower is provided with ordi-

nary bubble trays 83, connected by overflow pipes 84. The gas pipe 71 is connected in the side of the tower below the trays, while an oil inlet pipe 72 is connected in the side of the tower above the trays. As is common in absorbers, the gas flows upwardly and the oil flows downwardly. This countercurrent flow whereby the oil and gas are brought into intimate contact, causes the oil to reabsorb gas sufficiently to restore it to approximately the same gravity it had when entering the treater.

Another form of apparatus is shown in Figure 5. An upright tank 100 is provided with a relatively large central flume 101 resting on the bottom of the tank and extending through the head 102. The flume extends upwardly from the head 102 a sufficient distance to provide a gas chamber 103 having a gas outlet collar 104. An influent inlet pipe 105 extends through the side wall of the tank and into the flume near the bottom thereof. This pipe is provided with an upturned elbow 106. The inlet pipe may lead from a suitable preheater (not shown).

Above the inlet elbow 106, a plurality of staggered cross baffles 107 are mounted in the flume. Just above the head 102 an upwardly inclined baffle 108 may be installed so as to provide a narrow exit between its free edge and the wall of the flume. This baffle will retard the upward passage of the oil and coax with the baffles 107 in scrubbing out the occluded gas. A heater H' similar to heater H is connected with the flume by pipes 40' and 42' operating similarly to the pipes 40 and 42.

35 A cross partition 109 surrounds the flume above the pipes 105 and 40'. A similar cross partition 110 is mounted a substantial distance above the partition 109 and these partitions are provided with perforations 111 on opposite sides of the flume. The space between these partitions may be filled with filtering material to provide a filter D' similar to the filter D. An oil conducting pipe 112 leads from the partition 109, through the partition 110 and the head 102, and extends laterally into the flume immediately above the baffle 108. The oil accumulating above the baffle 108 enters and flows down this pipe so as to be discharged below the partition 109.

50 The influent which flows up the flume passes through a filter 113 similar to the filter D and this filter serves to break up the oil globules and release gas in solution with the oil. After the oil has been degassed in the flume, the gas escapes to the chamber 103 and the oil is discharged into the pipe 112. The flume corresponds to some extent to the degassing chamber A of Figure 1. The oil which is discharged into the chamber below the partition 109 passes up through the filter D' and the water is thus washed out of the oil.

60 The treated oil collects in the upper section of the tank and escapes through an outlet 114. A water discharge pipe 115 leads from the lower end of the tank and is connected with an ordinary adjustable water leg 116, whereby a water level is maintained in the tank. The water leg is usually installed in the field and is arranged by the workmen so as to maintain the desired water level for the particular installation. The water level in the flume is maintained by the heating arrangement.

70 The outlet 114 may be connected with the absorber K, or through the preheater C, if desired. Free water could be taken out of the bottom of the flume by a pipe 117 having a valve 118, or by 75 any suitable means.

Still another form is shown in Figure 6 which is in some respects similar to Figure 5 as it includes the tank 100, flume 101, baffle 108, partition 109, oil outlet 114, heater H' and heater pipes 40' and 42'. This form may have the water discharged as in Figure 5 and it is not considered necessary to illustrate the same. The tanks in both Figures 5 and 6 have a gas chamber M above the oil level.

At the upper end of the flume is a gas separator S similar to the separator J and having an influent inlet 120, a diverter 48, a dished bottom 121 and a gas outlet 122. A gas equalizing pipe 123 extends from the bottom 121 into the gas separator. A down pipe 124 leads from the bottom 121 down the flume and discharges adjacent the bottom thereof. The pipe passes through staggered baffles 125 similar to the baffles 107.

A discharge pipe 126 leads from the flume just above the baffle 108 and connects with a vertical stack 127. This stack has its lower end discharging through the partition 109 and its upper end above the pipe 126 closed by a cap 128 and constituting a gas space. The cap is connected with the gas separator S by a pipe 129. The partition 109 has perforations 109' on the opposite side of the tank from the discharge of the stack 127 so that the emulsified oil must flow across the tank to escape upwardly through said perforations, thereby giving the free water a better opportunity to drop out of the mixture while flowing across the tank under said partition.

A relatively large body of oil floats on the body of water in the mid portion of the tank. A filter 130 comprises filtering material 131 held between plates 132 and 133, similar to the filter D. Transverse baffles 134 depend from the plate 132 in staggered relation to transverse baffles 135 extending upwardly from the partition 109. The emulsified oil rising through the perforations 109' must flow over and under these baffles to reach the perforations 111 in the plate 132, thus causing additional water to drop out of the emulsified oil. The free and precipitated or separated water may be carried off in any suitable manner, as by means of the water leg 116 as is shown in Fig. 5.

The foregoing description of the invention is explanatory thereof and various changes in the size, shape and materials, as well as in the details of the illustrated construction may be made, within the scope of the appended claims, without departing from the spirit of the invention.

What we claim and desire to secure by Letters Patent is:

1. The method of treating emulsified oil well streams to defoam said streams and to break down the emulsion which includes, discharging the well stream directly into a body of heated water, flowing the emulsified oil through said body of water to heat said oil and primarily release gas therefrom, controlling the temperature of said water in accordance with the composition of the particular mixture being treated in order to release sufficient gas to eliminate foam, and thereafter washing the defoamed oil in a body of water heated to a temperature sufficient to break the emulsion.

2. The method of treating and defoaming emulsified well streams as set forth in claim 1, with the step of filtering the upwardly flowing emulsified oil to break up oil-gas globules and release additional gas.

3. The method of treating and defoaming emulsified well streams as set forth in claim 1, with the step of baffling the released gas.

4. The method of treating and defoaming emulsified well streams as set forth in claim 1, with the step of passing the well stream in heat exchange relation with the washed oil to preheat said stream and to cool said oil.

5. The method of treating and defoaming emulsified well streams as set forth in claim 1, with the step of carrying off free water from the well stream prior to the washing step.

6. The method of treating and defoaming emulsified well streams as set forth in claim 1, wherein gas is released from the stream prior to discharging said stream in the first body of water.

15 7. The method of treating and defoaming emulsified well streams as set forth in claim 1 with the step of reabsorbing the released gas in the washed oil.

8. The method of treating oil well emulsions 20 to defoam and to break down the emulsion which includes, passing the emulsified oil in intimate contact with a body of heated water while flowing the oil and water in counter-current relation to liberate gas in solution in the oil and thus defoam the emulsion, circulating and heating said water, carrying off the liberated gas separately from the oil and water, then washing the emulsion and oil in a second and more quiescent body of heated water to remove water therefrom, carrying off water, and carrying off the washed oil.

25 9. The method as set forth in claim 8, wherein the oil passing upwardly while flowing counter-currently in contact with the water is partially obstructed to break up globules containing gas to increase the liberation of the gas in solution.

10. The method as set forth in claim 8, with the step of passing the washed oil and liberated gas in intimate contact to reabsorb gas in the oil.

40 11. The method as set forth in claim 8, which includes discharging the emulsified oil into a body of water heated to a sufficient degree to liberate gas in solution and breaking up the oil globules to further release gas in solution, whereby foaming is minimized, collecting the released gas, carrying off the released gas, thermosyphonically circulating the water of said body, carrying off free water flowing with the emulsion, then washing the emulsified oil in a body of heated water, carrying off the treated oil, and then commingling the gas and treated oil which are carried off, whereby the treated oil reabsorbs such gas and its gravity is raised.

55 12. The method as set forth in claim 8, which includes discharging the emulsified oil into a body of water heated to a sufficient degree to liberate gas in solution and breaking up the oil globules to further release gas in solution, whereby foaming is minimized, collecting the released gas, carrying off the released gas, thermosyphonically circulating the water of said body, carrying off free water flowing with the emulsion, then washing the emulsified oil in a body of heated water, carrying off the treated oil, and passing the gas and oil which are carried off in intimate contact while flowing countercurrently to cause the treated oil to reabsorb gas for the purpose of raising the gravity of the oil.

60 13. The method of treating flowing oil well streams to break down emulsions and to eliminate foaming which includes, discharging the well stream directly into a body of heated water and flowing the emulsified oil therein to heat said oil and release gas therefrom, carrying off free water from said stream, filtering and baffling said emul-

sified oil to release gas therefrom, carrying off the released gas, then washing the emulsified oil in a body of heated water, carrying off the treated oil substantially free from water, and carrying off the water from the washing step.

14. The method as set forth in claim 13, with the step of passing the treated oil in heat exchange relation with the well stream to preheat said stream and to cool said oil.

15. The method as set forth in claim 14 with the step of reabsorbing released gas in the treated oil to raise the gravity thereof.

16. The method of treating emulsified oil well streams to defoam and to break down the emulsion which includes, discharging the well stream directly into a body of heated water and flowing the emulsified oil therein to heat said oil and release gas therefrom, controlling the temperature of said water in accordance with the composition of the particular mixture being treated in order to release sufficient gas to defoam the mixture, obstructing the upward flow of emulsified oil to further release gas therefrom, collecting and overflowing the oil above said body of water, then conducting the emulsified oil through a second body of heated water to break down the emulsion, and separately carrying off water and oil from the washing step.

17. In an apparatus for treating emulsified well streams and defoaming the stream, the combination of a vessel having a well stream inlet, means in said vessel for heating the emulsified oil to degas it and to eliminate foaming during the treatment, means for controlling the temperature of the heating means in said vessel, means for discharging released gas from said vessel, means in the vessel for breaking up oil-gas globules, means for overflowing defoamed oil from the vessel, a second vessel, a conductor for carrying the defoamed emulsified oil from the overflow of the first vessel to the lower portion of the second vessel, the second vessel containing a body of heated water into which the emulsified oil is discharged, means in the sec-

ond vessel for dispersing and baffling the emulsified oil as it flows upwardly through the body of water therein, an oil discharge leading from the second vessel, and a water discharge leading from the second vessel.

18. An apparatus for treating and defoaming emulsified oil well streams as set forth in claim 17, with means in the first vessel for retarding the upward flow of the influent therein to break up the emulsion.

19. An apparatus for treating and defoaming emulsified oil well streams as set forth in claim 17, with means for separating gas from the influent before it is discharged into the first vessel.

20. An apparatus for treating and defoaming emulsified oil well streams as set forth in claim 17, with an absorber connected with the gas outlet of the first vessel and the oil outlet of the second vessel.

21. The method of treating emulsified oil well streams to defoam said streams and break down the emulsions which includes, discharging the stream into a body of heated water, flowing the emulsified oil upwardly through said body of water to release sufficient gas therefrom to eliminate foaming, and thereafter washing the defoamed oil in a body of water heated to a temperature sufficient to break the emulsion.
